UNITED STATES PATENT OFFICE.

MILLER REESE HUTCHISON, OF BRONXVILLE, NEW YORK, ASSIGNOR TO LOVELL-McCONNELL MANUFACTURING COMPANY, A CORPORATION OF DELAWARE.

HORN AND SIMILAR INSTRUMENT.

1,111,463.

Specification of Letters Patent. Patented Sept. 22, 1914.

Application filed September 15, 1905. Serial No. 278,562.

To all whom it may concern:

Be it known that I, MILLER REESE HUTCHISON, a citizen of the United States, and resident of Bronxville, in the county of 5 Westchester and State of New York, have invented certain new and useful Improvements Relating to Horns and Similar Instruments, of which the following is a specification.

10 This invention relates to annunciator, alarm or musical horns or pipes, such as are commonly used for signaling a warning, alarm or other message and is adapted for uses analogous to those of automobile 15 horns, coach horns, bugles, calliopes, etc. It includes, broadly, a horn or similar resonating or amplifying device, preferably of the wind instrument type, means for exciting acoustic vibrations thereof, a motor 20 for operating said means and a system for controlling the same. At the present time, the air columns of resonators or horns for the purposes referred to are excited by a blast made pulsating or intermittent, usually 25 by a vibrating valve member, such as a reed or the lips of the player, the frequency or note being controlled and determined by the resonant reaction of the air column of the instrument upon the reed or other vibrating 30 member. These reeds must be delicate, in order to perform their function and where exposed to dirt and rough usages, as in the case of automobile horns, are frequently found out of order and in need of renewal 35 or repair at the very instant when they are most needed. From the nature of things, the reed must open for the passage of considerable quantities of air and will always open in response to the least back 40 pressure, as, for instance, by suction of the blast-producing device when refilling, or by high air pressure on the mouth of the horn, due to high speed, a high head wind or both. In high speed operation of the 45 auto, a comparatively high but varying pressure usually prevails within the horn. Thus particles of dirt, gravel, etc., are carried to the reed and cause it to fail to properly seat itself, thereby causing it to fail to act as a 50 valve and rendering it inoperative. Moreover the means for supplying the air blast, whether by a connection to the exhaust of the engine or by the more usual hand oper-

ated rubber bulb and flexible tube, are cumbersome, not easily installed or operated and especially in the case of the rubber bulb and tube, expensive and requiring frequent renewal.

I have devised my present invention with the object, among others, of providing a means for exciting the air column of the amplifier or resonator which does not require an air blast for its operation, is not liable to clogging by dirt or injury by jar- 60 ring, which is, or may be independent of 65 said air column, has no parts that are likely to wear out or deteriorate in the course of regular use, which is capable of modification of note to suit the taste or caprice of the 70 operator and which may be controlled without muscular exertion from any point, or independently from as many different points 75 as may be desired. As an alarm horn for 80 high speed automobiles, the latter feature in practice, it is frequently the case that a passenger, who sees the dangers in the way, but who can do nothing in the direction of assisting or advising the driver, may get a needed relief from nervous tension, without 85 in any way interfering with or discommoding the driver, by simply sounding the horn.

In the practice of my invention, the horn or amplifier may be of any known or desired construction. It is a means for determining or forming a column of air and preferably has pronounced natural fundamental and harmonic notes. The movable member employed as an exciter is preferably an imperforate diaphragm, closed against all air 90 drafts whereby all backward movement of air through the horn is prevented, and which cannot well be injured or put out of operation by dirt, gravel or rough usage. The motor for this diaphragm may be any desired form of electromagnetic or mechanical actuating means, suitably arranged for forcing it to pulsate at the desired frequency. The preferred motor or actuating means, is an electromagnet using a power current 100 adapted to cause a wide amplitude bodily vibration of the diaphragm as a whole. This electromagnet may be excited from any suitable source of current yielding a sufficient volume of said current, and the fluctuations 105 of the latter may be controlled in many dif-

ferent ways; as, for instance, by an automatic circuit breaking device, such as is used to make and break current through the primary of an induction coil.

5 As a simple automobile horn, it is desirable that current fluctuations, or impulses of the vibrator, be of a definite frequency, corresponding to one of the notes or natural periodicities of the horn. Where a vibrating circuit closer or buzzer is used, the desired frequency or note may be attained by adjusting the natural vibratory period of the latter, or by changing the elasticity, the weight or the effective length or the amplitude of oscillation of the vibrating member. In practice the former method is the preferred one.

Where desired, a plurality of excitors of different periodicities, corresponding to the chords of an octave beginning with the natural fundamental note of the horn, may be employed. The various frequencies may be caused to excite the main air column, either through separate branch tubes and diaphragms, or a plurality of circuit closers may be arranged in parallel and operated by separate circuits. With either of these arrangements, a set of four circuit closers, to be operated by the fingers of one hand, will be sufficient to control the production of any of the ordinary bugle calls. By merely multiplying parts and periodicities, so as to represent any desired number of notes, a keyboard, as complete and of as great range as desired, may be had. The notes produced are of greater volume and penetration than those of the ordinary air blast, reed-operated automobile horn and, by the before described arrangements, musical compositions may be rendered, comparing in these respects with the effects of a steam calliope.

Referring now to the drawings:

Figure 1 is a diagram of a complete controlling system, an automobile being indicated in dotted lines to show the locations which may be selected for the circuit closers. Fig. 2 shows an automobile horn and vibrating attachment in side elevation. Fig. 3 is a vertical section through the case of the vibrator and essential parts of the mechanism. Fig. 4 is an end elevation of the vibrator, with the rear cover of the case removed. Fig. 5 is a detail of the 3-point contact diaphragm buckling spring. Fig. 6 is a diagram, showing four vibrators operating on a single vibrating diaphragm. Fig. 7 illustrates an arrangement of 4 harmonic vibrators, applied to a single horn. Figs. 8, 9 and 10 are views corresponding to Figs. 2, 3, and 4 respectively but illustrating a modified arrangement.

In the drawings, the horn or resonator 1, for determining the oscillatory column of air, is shown mounted in the conventional manner in the usual location on the auto-

mobile, the latter being indicated in the dotted lines. The case 2 containing the vibrator, for exciting the horn, is mounted upon the small end of the latter and from it extend suitable circuit connections 3, 4. One of the wires or leads 3, has serially connected therein the battery 5, which may be one especially supplied for the purpose or which may be the storage battery commonly used for the igniter of an explosive motor and adapted to supply a comparatively heavy current. The wire 4, for completing the circuit, extends parallel with 3. In practice, these wires may be the ordinary twisted insulated pair of lead and return wire, commonly used in wiring houses, etc. Connected across this pair of wires, there may be as many normally open circuit closers as may be desired. For instance, there may be a circuit closer 6 upon the steering wheel, as shown and others, 7, 8, 9, 10, within convenient reach of each passenger. They may be arranged out of sight and covered by the leather of the upholstery, as indicated at 10.

The vibrator or exciter is compactly arranged in a durable dust tight case 2, preferably of light non-magnetic material, such as aluminum, and provided with a screw threaded opening on the front side, opposite the center of the diaphragm; the size of the opening and pitch of the thread being preferably standard and adapted to fit directly on horns now commonly used on automobiles. It will readily be understood that the operation of installing the device, on an automobile having an ordinary horn, is very simple. It is only necessary to unscrew the usual reed and screw on the diaphragm casing 2. A pair of twisted wires may then be led serially through a few battery cells, either storage or primary, and carried up the steering wheel and secured to any simple form of circuit closer, which may be clamped or otherwise fastened on the shaft, hub, spoke or rim thereof, in any desired manner. Such circuit closer may be of the type normally spring-pressed open and adapted to be positively closed, or it may be arranged to stay normally open or normally closed, as set by the operator.

Any one of the switches may be placed in series with a loud speaking telephone transmitter as, for instance, the transmitter 12, mounted on any suitable support 11, cushioned in any desired manner and serially connected with the switch 8, so that upon closing the latter the fluctuations of the transmitter are impressed upon the power current running the vibrator. Such a transmitter may be located in any desired position and may be arranged in operative relation to the reproducer of a phonograph. When the transmitter is to be used instead of the vibrating circuit closer within the 13

case, the latter will be screwed up or otherwise short circuited by the operator, in a manner hereinafter explained. Other pairs of wires and other controllers may be connected in parallel, after the manner of 7, 8, 9, 10.

The vibrator and horn may be assembled as shown in Fig 2 and sold as a unit, or each may be sold separately. Also, the horn and vibrator may, if desired, be assembled in a single structure as, for instance, the case, or any desired part thereof may be made an integral part of the horn.

The inner wall of the front cap 14 is preferably plane faced and back of the same; substantially parallel therewith and spaced away a short distance, is the diaphragm 22. On the back side of said diaphragm may be a 3-point contact buckling spring 23, and behind this adjustably mounted a resonating wall or partition 24, carried by a cylindrical flange 25, exteriorly screw threaded to fit the interior of the cylinder 13. In assembling this part of the device, the resonator wall 24 may be screwed in place, a paper washer 26 fitting over the end of the cylinder 13, the annular 3-point buckling spring, the paper washer 27, the diaphragm 22 and the paper washer 28 being then placed in position successively and the cap 14 forced thereover and secured by the screws 19.

The motor, or diaphragm vibrating device, comprises the longitudinally subdivided or laminated iron core 29, adapted to project through the opening 30, in the resonator partition 24, and surrounding said core is the coil or winding 31, held between non-conducting, preferably hard rubber, end pieces 32, 33. 32 is mounted upon a transverse segmental screw threaded bridge 34. Carried by this bridge is the vibrating circuit closing and circuit breaking device, for interrupting the current and causing pulsations in the coil of the electromagnet. It comprises a compound vibrating member, consisting of a main leaf spring 35, carrying an armature 36 of magnetic material, and a secondary spring 37, carrying a sparking contact 38. The latter contact may be of platinum, or platinum-iridium, and is adapted to contact with and close the circuit through a contact of similar material on screw 39 carried by the standard 40, which, like the other parts mentioned, is secured to the bridge piece 34 as, for instance, by screw 41. The free end of 40 is split to the screw 39 and is provided with a transverse pinching screw 42, for locking 39 in position. The vibrator is mounted upon an insulating block 43 by screw 44. A screw 45, tipped with or contacting with an insulating block 46, serves to adjust the normal position of the free end of the vibrator when at rest. The frequency of the vibrator may be changed greatly by adjusting this screw

45, whereas finer adjustments of frequency etc., may be made by adjusting the contact screw 39.

The screw 39 may be either locked by the screw 42, as described, or it may be left unlocked and free to be operated by a flexible shaft 47, leading to any desired point in the automobile and terminating in the handle 48. For pleasure parties the latter arrangement is interesting and amusing, it being 75 possible to get a wide range of notes by thus adjusting the screw 39, while in motion. It is quite practicable to play simple tunes in this way. This flexible shaft adjustment may also be used to permanently close the 80 circuit of the vibrator, when it is desired that some other fluctuation determining member, such as the loud speaking telephone actuated by the voice of the operator or other occupant of the car, or the phonograph, be substituted for the regular interruptions of the buzzer. When the flexible shaft is not used, the main function and the adjustment of the screw is, to determine and adjust the frequency of the 85 vibrator which may be that of a natural note of the horn, with which it is used. The latter is the more normal and businesslike use of the device and when the proper adjustment for such purpose is achieved, the 90 parts are preferably locked in position. To effect the adjustment of my vibrator direct to any horn, as that shown at 1, I first secure it to the small end of the horn, then connect the lead and return wires to the 100 post 49, 50, binding them between nuts 51, 52, which are properly insulated from the case by bushings 53, 54. The wires are then run serially through the battery and to one or more circuit controllers. The bridge 105 piece 34 is then screwed inwardly, until the core is quite close to the diaphragm 22. The vibrator is then set in operation, and the screw 39 turned in and out until the desired note is obtained. In practice, it 110 will always be found preferable to have this note one harmonious with a natural note of the horn. It is very easy to tell when such a note is attained, by reason of the increased loudness of the sound; and 115 also where the core is too close to the diaphragm, because the increased amplitude of vibration of the latter causes it to strike the core. The adjustment of screw 39 may then be fixed by the clamping screw 42 and the 120 frequency of the vibrator thus maintained at the desired note. The bridge piece 34 may then be adjusted out, until the diaphragm just clears it when vibrating most strongly. The space behind the diaphragm 125 is then adjusted to the space in front of it, and to the selected frequency which may correspond to a natural note of the horn, by turning said partition 24 to the right as far as it will go, by means of a spanner engag- 130

ing notches 56. Still keeping the horn in operation, the partition 24 is adjusted outwardly, by screwing slowly to the left, until the sound becomes much louder. When this is the case, the spaces in front and back of the diaphragm will be balanced for the maximum amplifying effect. By thus adjusting, first the vibrator and then the air space, to the frequency of the horn, remarkably 10 amplified vibration of the air column of the latter may be obtained.

I find that where the amplifying space or chamber on the back side of the diaphragm is quite small as compared with the length of the horn, there is a marked synchronized 15 amplifying effect when said space is properly adjusted as above described. In referring to this effect as a resonance effect, to the partition 24 as a resonant wall and to the space between such partition and the vibrator 20 22 as a resonant space, I do not intend thereby to exclude any reinforcing reaction in which vibration of the partition 24 may have a part, or any cushioning action which 25 the confined air may have relative to the air column of the horn or to the air in the space between the diaphragm 22 and the front of the casing. I make any openings which could pass air, such as that at 30, as small 30 as possible. I intend to cover all the possible operations of this part of the device in effecting amplification of vibration of the diaphragm 22 regardless of whether and to what extent such effects be resonance effects 35 or pneumatic cushioning effects or sounding board effects.

The effect of buckling springs, such as 23, is to give the effect of greater stiffness to the diaphragm and to determine the number 40 and position of the nodal points of the vibrations thereof. The number of sectors is always an even one and the effect of a three point contact arrangement, such as shown, is to cause the diaphragm to vibrate in six 45 sectors. The number may be increased by changing the number of such contact springs so that there will be 8—10—12—14—16, etc., 50 sectors, the ratio of frequency of vibration being as the squares of one-half the number of sectors, as for instance the squares of 2—3—4—5—6—7 and 8 respectively for the 4—6—8—10—12—14—16, etc., sectors.

From the above it will be evident that the 55 higher the frequency of movement desired for the diaphragm the greater will be the number of these contact springs 23. Where desired to tune the diaphragm to the frequency of a note of the horn, it may be accomplished by selecting a suitable thickness 60 and diameter for the diaphragm and then employing a suitable number of these damping contacts, the rate of vibration of the diaphragm itself being proportional to its thickness and inversely proportional to the 65 square of its diameter. What may be termed

a basic frequency may be determined by selecting a diaphragm of proper thickness and diameter and this basic frequency may in turn be modified in the manner above described. In so much as the horn and vibrator may be designed and constructed one for the other and sold as a unit, all adjustment may be made in the factory. 70

The note produced by my instrument is of great volume and carrying power and may 75 be made of good musical quality. The penetrating or carrying quality seems to be dependent on the sharpness of vibration of the diaphragm, whereas the finest musical quality requires somewhat less sharpness of 80 movement, resulting in a note of apparently not much less volume but of somewhat less carrying power.

Many of the details of the above described construction and arrangement of parts, are 85 worked out with a view to obtaining the maximum volume of sound, whether sharp and penetrating, or rounded and musical, while certain others of the details may be specialized to increase one or the other of 90 these qualities.

The volume of sound is in all cases improved by my particular arrangement of front closing cap 14 and opening therein. It would naturally be assumed that the 95 greatest volume of sound, as distinct from clearness, would result from making the coupling to the horn in the form of a converging cone, having a base approximately the size of the diaphragm and an apex the 100 size of the small end of the horn. I have discovered however, that the inner face of the case should be substantially parallel with the diaphragm, that the passage therefrom should be of about the diameter shown 105 and should be made straight or cylindrical. The diameter of the small end of the horn is practically fixed, by reason of its being adjustable to existing horns, and if the passage converged from the horn to the diaphragm the opening to the diaphragm chamber would be too small. Moreover I have 110 found that the opening should cover a certain area at the center of diaphragm, about as shown in the drawing. 115

Other factors of volume of sound are the amplitude and the abruptness of the current fluctuation in the coil. In order that these may be great, the winding 31 should be of low resistance and may be as low as $1\frac{1}{2}$ or 2 120 ohms. The reluctance of the winding and its iron core should be small and to this end the core may be formed of comparatively fine wire, which may be rusted to effect magnetic insulation. The make and break of the circuit closer should be positive and sharp and to this end, and also in order that it may not be disturbed by jarring of the vehicle, it should be formed with comparatively stiff springs of substantial dimension. 125 130

sions. The volume of sound is also greatly augmented by making the frequencies of the movements of the diaphragm the same as the frequency of one of the natural notes of the horn, the column of air in the horn in such case vibrating in sympathy with, and reacting on, the diaphragm, thus reinforcing and amplifying the forced movements caused by the electromagnet.

In order to get the best reinforcing and amplifying effect of the resonant air column, the diaphragm frequency should not be complex, but should be a single frequency. It may be made single by loading or tuning the diaphragm to the air column, but this method involves mechanical complications where frequency adjustment is desired and I have preferred not to tune the diaphragm, but, on the contrary, make its natural vibratory period relatively high by use of the 3-point contact buckling spring, so that its natural rate of vibration will be very high as compared with the intervals between the electrical impulses.

The low resistance winding of comparatively low inductance and the sharp make and break fluctuations in the magnet, which are most suitable for volume and penetration, may be modified in favor of musical quality, by considerably increasing the inductance of the winding, or using a separate tuning inductance in series therewith, which may be adjusted to the natural period of the horn, so that the rise of magnetism in the electromagnet operating the diaphragm, will be smoother and more gradual. In these ways fluctuations can be smoothed off, so that the periodic movements of the diaphragm will be slower and, if necessary, follow approximately a sine law. This causes some sacrifice of penetrating quality of the sound, but only a minimum sacrifice of volume at short ranges; but it may be compensated for by resonant rise of current, where a condenser is used, or by utilizing a source of greater electromotive force, giving greater amplitude of current, resulting in greater magnetization and of greater amplitude of movement of the diaphragm.

As before stated any desired number of horns may be combined to give any desired number of notes and several notes may be got from a single horn, either by attaching several complete vibrator cases thereto, or by having several outside circuit closers acting in parallel with each other, in series with a single coil 31 and diaphragm 32.

In Fig. 6 I have shown the latter arrangement, the horn 1 and case 2 being as usual, but the circuit closer, corresponding to 37, either short-circuited or removed. There are lead and return wires 3, 4, serially connected to the battery 5. Bridged across these wires, in parallel with each other, are a plurality of independent electro-magnetic

circuit closers diagrammatically indicated at 60, 61, 62 and 63. These circuit closers are each in series with the winding 31, in the case 2, and are controlled respectively by the circuit controlling keys 64, 65, 66 and 67, mounted upon a single key-board 68, adapted to be located in any desired position as, for instance, in place of any of the circuit controllers indicated in Fig. 1. Each of these vibrating circuit make and break devices is tuned in any of the ways hereinbefore indicated, preferably each to correspond to a different natural frequency of the horn, 1.

As this arrangement approximates and, in effect, constitutes a kind of musical instrument, and especially since one or more of the notes may be sounded at the same time, it will sometimes be found desirable to soften and smooth the vibrations, to improve the musical quality. This may be done by any of the expedients hereinbefore indicated. The inductance of each circuit breaking magnet may be increased, or an adjustable inductance may be placed in a part of the circuit common to all of the branches, or individual adjustable inductances may be inserted in each branch, or any of the expedients may be employed. For instance, the inductance 68' may be adjusted so as to smooth the fluctuations sufficiently to improve the quality of all the notes of the octave within the range of the key-board 68, and individual adjustable inductances 69, 70, 71 and 72 may be placed in each branch, to perfect the tuning more closely to the particular frequency of the fluctuations thereof. It is preferable and usually simpler to have most of the effective inductance used for tuning, in a single winding. For this reason it will sometimes be found desirable to put all of the inductance in the magnet winding, rather than to employ auxiliary inductance. The key-board 68 may also be used to operate the arrangement shown in Fig. 7 consisting of a group of four independent diaphragms and vibrators attached to a single horn 1 by four branches 74 extending out from a common coupling 16, adapted to be screwed to the horn. These branches are preferably at as small an angle as possible to the axis of the horn so as to avoid reflection and interference of the vibration in passing from the branches to the horn.

The construction of the automobile horn for purposes of amusement and recreation and to give forth harmonious notes, pleasing to the ear, is of great importance for the supply of certain of the demands of the trade, and not at all inconsistent with its use as a warning signal. For high speed automobiles, however, particularly for use in high speed road races and touring, the horn becomes a factor in the safety both of the

automobile and its occupants and of the regular traffic of the road, and the musical quality of its note should be made subservient to the alarm quality. I have hereinbefore described how the note may be made loud and yet perfected in pleasing musical quality to any desired degree, but in practice this very quality I have discovered to be inherently objectionable, because in a 5 sweet note or harmony of notes, however loud, there is a certain pleasing effect upon the ear and brain of the hearer which attracts attention readily enough, but which does not excite that instantaneous alarm 10 which is desirable. Safety at high speed requires not only that the sound be loud and concentrated but that it be harsh, disagreeable and penetrating, so as to cause in the mind of the hearer an instinctive, automatic, 15 reflex, physical impulse to get out of the way, without the necessity of any intermediate mental process of reasoning. For these purposes, all the expedients hereinbefore specified, regarding low impedance of the 20 coil, sharpness of the make and break and stiff, snappy movement of the diaphragm, should be employed and I have devised certain additional features, contributing to 25 further efficiency in this same direction.

30 The vibrating diaphragm may be almost entirely deprived of its pleasing quality by making its natural period high, particularly by making it stiff and snappy and also by use of the multiple contact spring hereinbefore described. Its note may be rendered 35 yet more alarming by causing vibratory impact thereon, at a rate corresponding to the desired note. One way of accomplishing this, is by adjusting the core of the electro- 40 magnet, so that the diaphragm will just touch it at the extreme limit of each inward movement, and when this is done the pole piece of the core should be slightly rounded, or should be provided with a rounded pro- 45 jection, so as to provide a single firm tapping contact at one point, adapted to break up and multiply the movements of the diaphragm, thereby making its note complex and harsh instead of simple, harmonic and 50 musical.

In Figs. 8, 9 and 10, I have shown a special modified form of tube and of vibrator case, adapted particularly for high speed work. In Fig. 8 the horn 1^a is modified to 55 more nearly approximate a tube, the sides being more nearly parallel and the flare at the end being entirely omitted. On the end of this horn may be screwed case 2^a, which may be provided with, or may be secured by 60 screws 61^a. The mechanism within the case 2^a, is modified in particulars which may be obvious from Figs. 9 and 10. The case comprises screw threaded cylinder 13^a, front closing cap 14^a and rear closing cap 15^a; a

segmental screw threaded bridge piece 34^a, 65 carrying electromagnet 31^a, having a core 20^a, projecting through partition 24^a. Front cap 14^a secures in place metallic washer 62^a, multiple contact spring 63^a, diaphragm 22^a and washer 64^a, all very much as in the form 70 first described, the case and diaphragm 22^a, however, being preferably of greater diameter.

The circuit is made and broken by movements of the diaphragm, to and from a 75 stationary contact maker 65^a adjustably secured in the support 66^a, projecting through the wall 16^a and insulated therefrom by the sleeve 67^a. A platinum iridium contact piece is rigidly secured to the diaphragm 80 and a corresponding contact piece of the same material is secured to the end of the member 65^a. The support 66^a projects outside the case and is secured by locknuts 69^a and 70^a shown in dotted lines in Fig. 10. 85 Outside of these is secured the circuit connection 71^a, by means of a nut 72^a, which may also be provided with a locking nut, if desired. The partition 24^a, is preferably formed with a forwardly set portion 24^b, setting up close to, and parallel with, the diaphragm 22^a. In this arrangement, the circuit 90 is normally closed from the battery connection 71^a, through the support 66^a the adjustable rigid abutment 65^a, the diaphragm 95 22^a, the case 13^a, bridge 34^a, coil connection 80^a, coil 31^a, connection 81^a, binding post 49^a and lead 82^a. As soon as the operator closes the outside circuit at any of the points shown in Fig. 1, the magnet is energized by 100 the current flowing as just described, the diaphragm 22^a is drawn downward and the circuit is broken, deenergizing the magnet and permitting it to snap back into contact with the rigid abutment 65^a, thus again closing the circuit. This operation is repeated 105 so long as the outside controller is closed, and every return movement of the diaphragm 22^a causes a sharp, snappy impact upon the stationary abutment 65^a. For the 110 high speed purpose, it will usually be found desirable to design and construct the tube 1^a and vibrator 2^a for each other and adjust them beforehand.

We may select a tube say $\frac{1}{2}$ inch in diameter at the small end, 2.7 inches at the large end and 19 inches long, sides being preferably along the straight lines of a cone as shown in Fig. 8 but flaring only about half as much as shown in that figure which has 115 been distorted by shortening about one-half from the dimensions above given. Such a horn will answer to a note approximately 3 feet long which is about low E, having a frequency of about 320 vibrations per second. 120 The diaphragm may be tuned to this frequency, but a higher one may be found more penetrating and more alarming. We may 125

therefore select a note six octaves higher, having a frequency of 1920 vibrations per second.

By selecting a diaphragm of proper thickness and elasticity and by use of the multiple contact springs hereinbefore described, the diaphragm may be tuned to 1920 vibrations. If the diaphragm selected has a natural free, vibratory period equal to the first mentioned fundamental period of the tube, it may be caused to sound any desired higher octave, by using diaphragm contact springs having the suitable number of contacts to form the desired number of sectors, which will give the higher note. Having turned the diaphragm 22^a in this way, the diaphragm 24^a is then adjusted in the manner previously described in connection with Figs. 2, 3 and 4. Everything may then be locked in position, as this form of the device is intended for maximum efficiency as an alarm, rather than for ready adjustment to suit the caprice of the operator. When thus arranged, the note will have all of the characteristics desirable for maximum efficiency as an alarm and, the constants being once determined, duplication of the construction and arrangement is easy.

The tube 1^a has a plurality of complete half waves of sound within its length and for this reason and also because of the omission of flare at the end, throws a great volume of sound, of penetrating quality, almost directly ahead.

The tuning of the vibrator frequency, or of the diaphragm frequency, with respect to the horn, may be perfected in whole or in part by changing the effective length of the air column of the latter. This may be accomplished in a variety of ways, as for instance, by clipping off or adding to the large end of the horn shown in Fig. 8, or by lengthening or shortening a section at the smaller end of either form of horn. A considerable range of adjustment is also possible by screwing the vibrator case outwardly and inwardly at its point of screw-threaded coupling to the horn or, where desired, an intermediate adjustable telescopic section of horn may be used. In fact change of the effective length of the air column of the horn may be accomplished by any known or desired expedition which is or may be employed for adjusting musical horns of the conventional type.

While I have very fully and accurately described and shown my invention, it is nevertheless a broad one and I intend to claim all equivalents and I do not limit myself to any specific forms or elements not specified in the claims hereof.

I claim as my invention:

1. In a device of the class described, a casing having a substantially plane front wall

and a diaphragm substantially parallel therewith and spaced therefrom a distance slightly greater than that of maximum amplitude of vibration of the horn, in combination with means for vibrating said diaphragm at a definite frequency and an adjustable wall forming with said case a resonant chamber adjusted to said definite frequency.

2. In a device of the class described, a substantially dust tight casing and a diaphragm secured therein, in combination with an electromagnet, interrupter and resonant wall behind the diaphragm, all separately and independently adjustable, for the purpose described.

3. An acoustic instrument, comprising a horn diaphragm and means for vibrating the same at a definite rate in combination with walls, forming approximately equal inclosed air spaces or chambers, at the front and back thereof, the front wall being substantially parallel with said diaphragm and the rear wall being adjustable with respect to said diaphragm.

4. An acoustic instrument, comprising a horn diaphragm and means for vibrating the same at a definite rate in combination with walls forming air spaces or chambers at the front and back thereof, said spaces being balanced for maximum amplified vibration of the diaphragm when vibrating at said rate.

5. An acoustic instrument, comprising a horn diaphragm and means for vibrating the same, in combination with walls forming air chambers or spaces at the front and back thereof, and means for adjusting said spaces to produce maximum amplification for vibrations of a selected definite rate.

6. An acoustic instrument, comprising a horn diaphragm and means for vibrating the same, in combination with walls forming air spaces or chambers at the front and back thereof, the rear wall being in a position of maximum amplification for vibrations of a selected definite rate.

7. An acoustic instrument, comprising a casing and, inclosed therein, a diaphragm, a vibratory interrupter and an electromagnet having a core in operative relation to both, in combination with a wall or partition behind said diaphragm adjustable independently thereof and forming with said casing a substantially closed air chamber at the back of said diaphragm.

8. An acoustic instrument, comprising a casing and, inclosed therein, a diaphragm, a vibratory interrupter and an electromagnet having a core in operative relation to both, and walls arranged to form air spaces at the front and rear of the diaphragm, adjusted for maximum amplification for vibrations of a selected definite rate.

9. An acoustic instrument, comprising a casing and, inclosed therein, a diaphragm, a vibratory interrupter and an electromagnet, having a core in operative relation to both, in combination with walls forming air spaces or chambers at the front and back thereof, and means for adjusting said spaces to maximum resonance for vibrations of a selected definite rate.
10. An acoustic instrument, comprising a casing and, inclosed therein, a diaphragm, a vibratory interrupter and an electromagnet having a core in operative relation to both, and a partition or wall in the rear of said diaphragm, and means for adjusting it to a position of maximum resonance for vibrations of a selected definite rate.
11. A horn or pipe and a casing, in combination with and inclosing a movable member, a vibrator of definite frequency and an electromagnet in operative relation to each, together with means for adjusting the frequency of the vibrator to a natural note or acoustic frequency of a horn, and means for simultaneously adjusting said vibrator and the core of said magnet away from the movable member, to compensate for the increased amplitude of vibration of the latter when the frequency is so adjusted.
12. A horn or pipe and a casing adapted to be secured over the end of said horn or pipe and in combination with said casing and inclosed thereby, a diaphragm, a vibrator of definite frequency and an electromagnet having its core in operative relation to each, together with means for adjusting the frequency of the vibrator to a natural note or acoustic frequency of a horn, and means for simultaneously adjusting said vibrator and core away from the diaphragm, to compensate for the increased amplitude of vibration of the latter when the frequency is so adjusted.
13. An attachment for horns comprising a dust tight case provided with an opening and a screw threaded tubular projection in combination with a diaphragm, an electromagnet and an adjustable vibrating circuit breaker within said case in operative relation to each other and to said opening, said electromagnet and circuit breaker and adjusting means for the latter, being mounted on a single support for adjustment to and from said diaphragm.
14. A signaling device, comprising an acoustic vibrator, electrically actuated means for vibrating the same, a plurality of frequency controlling means in operative relation to said vibrating means, and means for independently actuating each of said controlling means.
15. A signaling device comprising a diaphragm capable of vibrating at any one of a considerable range of frequencies, vibration-producing means in operative relation to said diaphragm, and a plurality of independently operating frequency-determining members electrically connected to said vibration-producing means, each of said members being adapted to control said vibration-producing means so as to produce vibrations of a particular frequency in said diaphragm.
16. A horn or similar means, adapted to determine a resonant air column and a diaphragm in operative relation to said air column, in combination with an electrically energized motor for said diaphragm and a plurality of circuit controllers of definite frequency in parallel with each other and in series with said motor and a source of electromotive force, together with independent controlling switches in each of said parallel branches.
17. A horn or similar means adapted to determine a resonant air column and a diaphragm in operative relation to said column, in combination with an electro-magnet for moving said diaphragm and a plurality of circuit controllers of definite adjustable frequency connected in parallel with each other and in series with said electro-magnet, together with means for controlling independently the operation of each of said circuit controllers.
18. A horn or similar means adapted to determine a resonant air column and a diaphragm in operative relation to said column in combination with an electromagnet for moving said diaphragm and a plurality of automatic vibrating make and break devices connected in parallel with each other and in series with said electromagnet together with a switch in each of said parallel circuits.
19. A horn adapted to transmit a wide range of frequencies and to resonate more strongly to certain selected definite frequencies, a diaphragm for one end of said horn and an electromagnet for actuating said diaphragm, in combination with means for energizing said magnet at a desired definite single frequency and other means independent thereof for energizing said magnet by complex fluctuations, said latter means consisting of a microphonic resistance and means for throwing said microphonic resistance in and out of circuit with said magnet energizing means.
20. A horn adapted to transmit a wide range of frequencies and to resonate more strongly to certain selected definite frequencies, a diaphragm for one end of said horn and an electromagnet for actuating said diaphragm, in combination with means for energizing said magnet at a desired definite single frequency and other means independent thereof for energizing said magnet by complex fluctuations said latter means comprising a microphone of the loud speaking

transmitter type and switch-control means for passing currents of considerable amperage serially through the latter and through said electromagnet.

- 5 21. In an acoustic instrument, the combination of a horn, a diaphragm, an apertured front wall forming with said diaphragm an annular air space or chamber at the front of the latter, a sound projector carried by said front wall, a back wall adjacent to said diaphragm and forming therewith an air compression space or chamber in the rear thereof and having a comparatively small aperture therethrough, and electrically operated means positioned in the rear of said back wall and having a portion projecting through said aperture and substantially closing the latter and operatively disposed in respect to said diaphragm to force upon the latter bodily movements or vibrations of high frequency and of sufficient amplitude to generate a loud warning signal.

22. In an acoustic instrument, the combination of a horn, a diaphragm, an apertured front wall forming with said diaphragm an annular air space or chamber at the front of the latter, a sound projector carried by said front wall, means for forcing upon said diaphragm bodily movements or vibrations of high frequency and sufficient amplitude to generate a loud warning signal, a back wall adjacent to said diaphragm and forming therewith a substantially closed air compression space or chamber in the rear thereof substantially continuous and substantially unobstructed and comparatively shallow in respect to the diameter of said diaphragm.

Signed at New York city in the county of New York and State of New York this 1st day of Sept. A. D. 1905.
